CLAIM

We claim the ornamental design for a “filter cartridge with handle end,” as shown and described.

DESCRIPTION

FIG. 1 is a front view of the filter cartridge with handle end according to the present invention;

FIG. 2 is a rear view of the filter cartridge with handle end according to the present invention;

FIG. 3 is a left-side view of the filter cartridge with handle end according to the present invention;

FIG. 4 is a right-side view of the filter cartridge with handle end according to the present invention;

FIG. 5 is a bottom view of the filter cartridge with handle end according to the present invention;

FIG. 6 is a top view of the filter cartridge with handle end according to the present invention;

FIG. 7 is a downward perspective view of the filter cartridge with handle end according to the present invention; and,

FIG. 8 is an upward perspective view of the filter cartridge with handle end according to the present invention, rotated 90° with respect to the orientation of FIG. 5.
